UNITED STATES PATENT OFFICE

GUY L. ROSEBROOK, OF ROSELLE PARK, NEW JERSEY

DESIGN FOR A SERVICE STATION

Application filed March 3, 1931. Serial No. 38,911. Term of patent 14 years.

To all whom it may concern:

Be it known that I, GUY L. ROSEBROOK, a citizen of the United States, residing at Roselle Park, in the county of Union and State of New Jersey, have invented a new, original, and ornamental Design for Service Stations, of which the following is a specification, reference being had to the accompanying drawing, forming part thereof.

The figure is a perspective view of a service station, showing my new design.

The opposite side of the design may be the same as the side illustrated or it may be plain.

I claim:

The ornamental design for a service station, as shown and described.

GUY L. ROSEBROOK.
